(57) **CLAIM**

The ornamental design for a boot cuff, as shown and described.

DESCRIPTION

FIG. 1 is a top, front, medial side perspective view of a boot cuff showing a first embodiment of the design.

FIG. 2 is a medial side elevation view of the boot cuff of FIG. 1.

FIG. 3 is a lateral side elevation view of the boot cuff of FIG. 1.

FIG. 4 is a front elevation view of the boot cuff of FIG. 1.

FIG. 5 is a rear elevation view of the boot cuff of FIG. 1.

FIG. 6 is a top plan view of the boot cuff of FIG. 1.

FIG. 7 is a bottom plan view of the boot cuff of FIG. 1.

FIG. 8 is a top, front, medial side perspective view of a boot cuff showing a second embodiment of the design.

FIG. 9 is a medial side elevation view of the boot cuff of FIG. 8.

FIG. 10 is a lateral side elevation view of the boot cuff of FIG. 8.

FIG. 11 is a front elevation view of the boot cuff of FIG. 8.

FIG. 12 is a rear elevation view of the boot cuff of FIG. 8.

FIG. 13 is a top plan view of the boot cuff of FIG. 8.

FIG. 14 is a bottom plan view of the boot cuff of FIG. 8.

FIG. 15 is a top, front, medial side perspective view of a boot cuff showing a third embodiment of the design.

FIG. 16 is a medial side elevation view of the boot cuff of FIG. 15.

FIG. 17 is a lateral side elevation view of the boot cuff of FIG. 15.

FIG. 18 is a front elevation view of the boot cuff of FIG. 15.

FIG. 19 is a rear elevation view of the boot cuff of FIG. 15.

FIG. 20 is a top plan view of the boot cuff of FIG. 15.

FIG. 21 is a bottom plan view of the boot cuff of FIG. 15.

FIG. 22 is a top, front, medial side perspective view of a boot cuff showing a fourth embodiment of the design.

FIG. 23 is a medial side elevation view of the boot cuff of FIG. 22.

(Continued)

FIG. 24 is a lateral side elevation view of the boot cuff of FIG. 22.

FIG. 25 is a front elevation view of the boot cuff of FIG. 22.

FIG. 26 is a rear elevation view of the boot cuff of FIG. 22.

FIG. 27 is a top plan view of the boot cuff of FIG. 22; and,

FIG. 28 is a bottom plan view of the boot cuff of FIG. 22.

The broken lines depict portions of the boot cuff that forms no part of the claimed design and portions of a boot, which contains the boot cuff, that form no part of the claimed design.

The stippled shading depicted in Embodiment 2 (FIGS. 8-14) continues across the entire surface of the claimed boot cuff. The oval elements depicted in Embodiment 3 (FIGS. 15-21) represent a flat surface pattern. The drawings are shaded to indicate contrasting surfaces.

1 Claim, 24 Drawing Sheets
